FOREIGN PATENT DOCUMENTS

DE	3520187	12/1986
GB	2085789	5/1982
WO	0006347	2/2000

Primary Examiner — T. Chase Nelson*Assistant Examiner* — Michelle E Wilson(74) *Attorney, Agent, or Firm* — Ohlandt, Greeley,
Ruggiero & Perle, LLP(57) **CLAIM**

The ornamental design for a window scraper, as shown and described.

DESCRIPTION

FIG. 1 is an isometric view of a window scraper according to the present disclosure;

FIG. 2 is a front view of the window scraper of FIG. 1;
FIG. 3 is a back view of the window scraper of FIG. 1;
FIG. 4 is a first side view of the window scraper of FIG. 1;
FIG. 5 is a second, opposite side view of the window scraper of FIG. 1;FIG. 6 is a top view of the window scraper of FIG. 1; and,
FIG. 7 is a bottom view of the window scraper of FIG. 1.
The broken lines depict portions of the window scraper that
form no part of the claimed design.**1 Claim, 6 Drawing Sheets**| (56)	References Cited
